OFFSET-WEB MECHANISM.

1,285,842.

Specification of Letters Patent.

Patented Nov. 26, 1918.

Application filed March 9, 1917. Serial No. 153,545.

To all whom it may concern:

Be it known that I, ISIDOR TORNBERG, a citizen of the United States, residing at New York city, county of Kings, and State 5 of New York, have invented certain new and useful Improvements in Offset-Web Mechanism, fully described and represented in the following specification and the accompanying drawings, forming a part of the 10 same.

This invention relates to certain improvements in offset web mechanism for rotary printing machines.

In certain classes of printing machines in 15 which the printing is effected by sets of printing mechanisms each including printing and perfecting couples, and ordinarily known as two-roll machines, it is desirable to use a traveling offset web interposed between the freshly printed side of the web and the second impression cylinder of each set of printing and perfecting cylinders, to prevent offset of ink upon the blanket of the impression cylinder, which offset would 20 cause a smut or smudge upon the following web. In order to obtain printing of very fine quality, such as letter press, it is desirable to provide an offset web for each of the sets, to insure no ink being deposited 25 on the impression cylinders.

The use of two separate offset rolls, however, has the disadvantage of imposing more care by the press operator, as these offset rolls have to be braked when the press is 30 stopped or slowed down or otherwise manipulated in the same manner as the other operating parts of the press. Furthermore, there is valuable time consumed in attending to the charging of the two rolls so that 35 after being wound up they will unwind in reverse position to present a fresh side to the web. In many classes of printing, however, where the quality does not have to be as fine as letter press work, for instance, 40 there is no necessity for the use of an offset roll for each of the second couples, one such roll preventing offset for both of the couples sufficiently for the purposes required. In many instances, it happens that 45 a printer will desire to print both high quality work, requiring two offset rolls, and 50

a somewhat lower grade of work, requiring but one offset roll. If, however, the machines as heretofore constructed are built for but one offset roll, they cannot, without considerable change in the mechanism, be made so that two offset rolls may be used. 55

The invention has for its especial object the provision of an arrangement whereby in a printing machine employing two sets 60 of printing mechanism, each set including printing and perfecting couples, either two offset web rolls may be employed, one for each of the second couples of each set, or one offset web roll may be employed for the 65 second couples of both sets, without requiring any changes in the mechanism by which the result is effected, or any changing or shifting of the mechanism, and without the addition of any parts. 70

For a complete understanding of the invention, reference may be made to the accompanying drawing, in which—

Figure 1 is a diagrammatic side elevation of a two-roll printing machine, that is, a 75 printing machine having two sets of printing mechanisms, each including a printing and perfecting couple, showing the improved arrangement where two offset rolls are employed, one for each web; 80

Fig. 2 is a diagrammatic side elevation of the second or upper printing couples shown in Fig. 1, illustrating the improved arrangement where one offset web roll is employed for the second printing couples of each set; 85

Fig. 3 is a view similar to Fig. 2, showing the run of one offset web after it has been once used and rewound ready for another passage through the machine.

Referring now to the drawings, the invention has been illustrated in connection with a rotary web printing machine of the class known in the art as a two-roll machine, in which there are two sets of printing and perfecting couples 1, 2, 3, 4, each 95 couple including form cylinders 5 and impression cylinders 6, each of the sets of couples being supplied from web rolls 7, 8. The form rolls 5 are inked in any usual manner by inking mechanism 9.

Machines constructed in accordance with the invention will have the sets of couples

spaced apart and in the space between the sets, so as to be between the web paths, will be located a pair of offset web roll supports. These supports may be of any suitable character, as frames 10, 11 arranged back to back and provided with lipped grooves 12 for receiving the spindles 13 of the offset rolls. The supporting frames 10, 11 may be of any suitable character, and as shown are made part of the side framework 14 of the machine. The supports are duplicated on the other side of the machine, being part of the side frame thereof, the space between the side frames at this point 15 being left open and free for the offset web to pass therebetween for a purpose herein-after referred to. Located adjacent the supporting frames at opposite ends is a pair of offset roll spindle supports which may 20 be in the form of rolls 15 for receiving the empty spindles 13 on which the offset web is rewound after it has been passed through the machine.

In machines constructed in accordance 25 with the invention, guiding means will be provided whereby a separate offset web may be led between the second printing couples of each set, as the couples 2, 4, and back to separate rewinding spindles, or one offset 30 web may be led through both of the second printing couples of each set and back to one spindle. These means may be of any desired character. In the particular construction illustrated, referring first to Fig. 35 1, there is shown two offset rolls, one for each of the second printing couples. These rolls are marked 16, 16' and are supported in the grooves of the frames 10, 11. The offset web, as, for instance, web 16', is led 40 over guide rolls 17 between the paper web and the impression cylinder 6 of the printing couple 2, so that it will be between the impression cylinder and the freshly printed side of the web, the offset web being then 45 rewound on one of the spindles 13. The other offset web 16 is similarly led over suitable guide rolls 18 between the other paper web and the impression cylinder 6, of the printing couple 4 and back to the other rewinding spindle 13. If, now, it be desired 50 to produce a somewhat lower grade of printing, necessitating but one offset web roll, a single offset web may be led between the second couples of each set, suitable guides 55 being provided for this. Such a construction is illustrated in Figs. 2 and 3. Referring to these figures, an offset web roll, as 16, is supported in the frame 11 and led over the guide rolls 17 between the paper web 60 and impression cylinder of the couple 2, then over a guide roll 19 located in the side frames above the web roll supports and down under the frames 11 and 10 and about midway thereof to and over the guide rolls 65 18, by which it is guided between the other

paper web and the impression cylinder of the second printing couple 4 and back to a rewinding spindle 13 located adjacent the frame 10. After the offset web is passed through the machine and has been rewound 70 on spindle 13, it is transferred to the supporting grooves 12 of the frame 10 and run through the machine in the reverse direction to that shown in Fig. 2, as illustrated in Fig. 3, it being rewound on a spindle 21 75 located adjacent the frame 11.

It will be seen from the construction described that an improved arrangement has been produced by which either one or two offset rolls may be used in a machine with- 80 out necessitating any mechanical changes or adjustments and a very simple and effective construction produced. It will also be understood that changes and variations may be made in the specific construction of 85 the various parts and that the invention is not to be limited to the precise details shown.

What is claimed is:

1. In a printing machine, the combination 90 with a plurality of sets of printing and perfecting couples, each set including form and impression cylinders of a source of web supply for each set, a pair of offset web roll supports and means whereby a pair of offset webs may be led from the supports through the second couple of each set or one offset web may be led from one of the same supports through the second couple 95 of both sets.

2. In a printing machine, the combination 100 with a plurality of sets of printing and perfecting couples, each set including form and impression cylinders, of a source of web supply for each set, a pair of offset web 105 roll supports located between the web rolls, and means whereby a pair of offset webs may be led from the supports through the second couple of each set, or one offset web may be led from one of the same supports 110 through the second couple of both sets.

3. In a printing machine, the combination 115 with a plurality of sets of printing and perfecting couples, each set including form and impression cylinders, of a source of web supply for each set, a pair of offset web roll supports located between the web paths, supports for offset web roll spindles adjacent the supports, and guides whereby a pair 120 of offset webs may be led from the supports through the second couple of each set to each of the spindle supports or one offset web may be led from one of the same supports through the second couple of both sets to one of the spindle supports.

4. In a printing machine, the combination 125 with a plurality of sets of printing and perfecting couples, each set including form and impression cylinders, of a source of web supply for each set, a pair of frames for 130

supporting offset web rolls located between the web paths, rolls for the offset web roll spindles adjacent the supports on opposite sides thereof, guides for leading a pair of offset webs from the roll supports through the second couple of each set to each of the spindle supports, and guides for

leading one offset web from one of the same supports through the second couple of one set to and through the second couple of the other set and back to one of the roll spindles.

In testimony whereof, I have hereunto set my hand.

ISIDOR TORNBERG.
